United States Patent Office.

GEORGE S. PIERCE, OF WILKESBARRE, PENNSYLVANIA.

Letters Patent No. 97,549, dated December 7, 1869.

IMPROVEMENT IN DEVICE FOR FORMING BOILERS.

The Schedule referred to in these Letters Patent and making part of the same.

To all to whom it may come:

Be it known that I, GEORGE S. PIERCE, of the borough of Wilkesbarre, county of Luzerne, and State of Pennsylvania, have invented a new and improved Device for Forming Boilers of any metallic substance.

The invention is an improvement in devices for forming boilers; and I hereby declare that the following is a full, clear, and explicit description of the construction and operation of the same, reference being had to the annexed drawings, making a part of this specification.

In Figures 1, 2, 3, 4, H represents a bench.

In fig. 1, A represents a square shaft, of any size, and shaped to form to two right angles.

m m represent mortises, in the upright part of A.

B B represent plates of segmental form, of any thickness, inserted in the mortise at the top of shaft A, being held by a pin so as to allow them to be joined or separated on the top of the shaft A.

c c represent arms, one end fastened to the plates B B, the other end of the arms each having a mortise, and passing through the mortise *m* in the shaft A.

S represents a thumb-screw, passing through mortise *m* and arms *c c*, to regulate the segmental plates and fasten them.

T, a thumb-screw, to hold the plate-iron to the shaft A, and permit it to slide up and down.

D represents an iron follower or plate, with a cup on the upper end, with a long mortise, and placed on the back part of shaft A, and held by the thumb-screw T.

To enable others skilled in the art to make and use my invention, I will proceed to describe its construction and operation.

The bench H represents any ordinary tool-bench. The lower end of the right-angled shaft A, made of iron, of any size, square, having a mortise in the top of the shaft; another about the centre of the upright part. The lower part is inserted in a hole in said

bench H, far enough from the edge of the bench to let the horizontal part of the shaft A rest on the bench and have the upright part of the shaft A stand vertical over the edge of the bench.

The plates B B, made of iron, of any thickness, are then, one end of each inserted and fastened by a pin in the upper mortise *m* of shaft A, and fixed so as to move easily.

The arms *c c* are then fastened to the opposite ends of each plate, and inserted in the mortise *m* of shaft A, and used to move the plates B B, and so adjust them as to enlarge or diminish the circle formed by them.

The thumb-screw S is used to fasten the arms *c c*. The follower D is placed on the side of shaft A, and is held by the thumb-screw T, and by the mortise *m*, is permitted to slide up or down, so as to bring the cap on the end of said D down on the segments B B.

To form a boiler, the arc or circle is formed by the adjustment of the segments B B, by the arms *c c*, and fastened by the thumb-screw S.

The tin or other metallic substance is then placed on the said arc, over the point where the segments B B join, and the follower cap D is then slid down upon it and fastened by the thumb-screw T, so as to hold the tin, &c., to its place. The tin or other metallic substance is then bent to conform to the said arc or segments B B.

What I claim as my invention, and desire to secure by Letters Patent, is—

The shaft A, with its two mortises *m m*, segmental plates B B, with arms *c c*, set-screw S, follower D, with its cap and mortise, and fastened with the thumb-screw T, arranged as described.

GEORGE S. PIERCE.
